(57) **CLAIM**

The ornamental design for a packaging material, as shown and described.

DESCRIPTION

FIG. 1 is a top isometric view of the packaging material;

FIG. 2 is a first end view of the packaging material;

FIG. 3 is a second end view of the packaging material;

FIG. 4 is a bottom view of the packaging material;

FIG. 5 is a top view of the packaging material;

FIG. 6 is a first side view of the packaging material; and,

FIG. 7 is a second side view of the packaging material.

In FIG. 1, the broken line represents the boundary of the claim; all other broken lines in the drawing depict environmental subject matter only. The broken lines form no part of the claimed design.

FIGS. 6-7 have been shown broken away to fit the disclosure onto the drawing page.
